UNITED STATES PATENT OFFICE.

WALTER D'ARCY RYAN, OF SCHENECTADY, NEW YORK.

LENS FOR VEHICLE LAMPS.

Application filed December 27, 1926. Serial No. 157,197.

My invention relates to improvements in headlights, and is particularly concerned with improvements in headlights for automotive vehicles.

5 The objects of my invention are:

First, to provide a headlight that is substantially non-glare but which, at the same time, provides adequate illumination not only in the immediate foreground, but also 10 at a considerable distance ahead of the vehicle carrying the headlight, and also provides lateral illumination of sufficient intensity to enable the driver to see curbs, ditches, road signs, etc.;

15 Second, to provide a headlight, such as described, that is simple in construction and economical to manufacture; and

20 Third, to provide a headlight having the characteristics set forth above that embodies a novel type of lens, or closure.

Other objects of my invention will appear as this description progresses, reference being had to the accompanying drawings, in which

25 Figure 1 is a front view of the lens forming a part of my improved headlight. Fig. 2 is a horizontal section therethrough on the line 2—2 of Fig. 1, and showing, in addition, the reflector forming a part of my improved 30 headlight. Fig. 3 is a vertical section taken on the line 3—3 of Fig. 1. Fig. 4 is an enlarged sectional detail taken on substantially the line 2—2 of Fig. 1, but looking in the opposite direction from that in which the 35 section in Fig. 2 is taken.

The reflector 10 of my improved headlight is preferably of the form described and claimed in my co-pending application, Serial No. 88,911, filed February 17, 1926, but may,

40 if desired, be given other forms and characteristics, although it should, in general, have the characteristics of the reflector referred to as being described in my previously filed application.

45 This invention relates particularly to a lens comprising means for spreading some of the light from the side portions of the beam toward the central portion thereof so as to improve the light distribution in the central 50 portion of the beam. At the same time, by providing prismatic surfaces adapted to refract a large portion of the light from the source for spreading it over the foreground immediately in front of the vehicle and also 55 into the sides of the road so as to reduce the contrast between the illumination of areas

immediately adjacent the road, and also eliminate any darkened areas within the spread of the beam.

In that embodiment of my invention disclosed herein, the lens comprises an outwardly bulging portion 11, substantially co-extensive with the mouth of the reflector, that is approximately in the form of a flattened cone having a rounded apex 11' and provided 60 with a marginal, rearwardly extending flange 12 that is preferably sand blasted or otherwise adapted to diffuse all light falling thereon.

A series of prisms extends across the portion 11 of the lens, being formed upon the inner side thereof, and this series of prisms is divided into the two side groups 14 and 15 and the central group 16. The prisms of each group, with the exception of those of the central group, comprise a convex face 17 and a flat face 18. All of the flat faces 18 are substantially parallel with the axis of the lens, although they may be slightly inclined to facilitate the manufacture of the lens. 70

While the convex faces 17 of the prisms do act upon the direct light from the source 13 to tend to bend this light toward the axis of the beam, the principal function of these convex faces is to direct the light reflected from the reflector 10 into the central portion of the beam in order to increase the intensity of that portion. The flat faces 18 intercept relatively little of the light reflected from the reflector but receive most of the direct light 90 from the source 13 and refract it outwardly so as to prevent the formation of darkened areas or non-illuminated areas along the side of the road within the driving range of the headlights. 95

It will be observed that the prisms on opposite sides of the center of the lens are inclined in opposite directions, that is, the convex faces 17 are thus inclined, and from an inspection of Figs. 2 and 3, it will be noted 100 that the prisms of the central group are fully convex.

From an inspection of Fig. 4 it will be further noted that the refractive power of the prisms in the side groups, increases from the inner prisms of each group outwardly to the outer prisms of that group, the refractive power of the prisms forming the central group being substantially constant.

In order to more specifically describe the 110 particular embodiment of the invention as shown in the accompanying drawings, but

without desiring to limit the invention thereto, I have shown herein its commercial embodiment. The prisms indicated by *a* have their convex face formed with a radius of .176 inches, their flat face being .05 inches deep. The group *b* is formed with a radius of .21 inches and a depth of .04 inches. The group *c* is .235 inches in radius and .032 inches in depth. The group *d* is .28 inches in radius with .03 inches in depth. The group *e* has a radius of .35 inches and a depth of .025 inches. The group *f* has a radius of .415 inches, while the depth is .02 inches, and the group *g* has a radius of .135 inches with a depth of $1/64$ th of an inch. Each of the prisms shown are made $1/8$ th of an inch wide in a lens having a thickness of $1/8$ th of an inch. From the foregoing it will be apparent that the radius of the prisms forming the side groups increases from the side toward the center, with a corresponding decrease in refractive power.

It will be noted that the arrangement of the prisms is such as to cover the sides and bottom portion of the lens, leaving the upper portion free from any obstruction or refraction of the light rays passing therethrough, as indicated at 19. This gives a "clear vision" window through which the light rays reflected from the upper portion of the reflector may freely pass so as to throw a concentrated white bright light down the road. However, the lateral spread of the light reflected from the side portions of the upper half of the reflector will be intercepted by the prisms extending to the top of the lens on each side of the clear portion 19, such lateral diverging rays being refracted and directed toward the center of the beam so as to be superimposed thereon.

It will be further noted that a reflector such as disclosed in my above-mentioned co-pending application Serial No. 88,911, will project a substantially crescent-shaped beam, the beam projected by the lower half of the reflector being inverted and superimposed upon the beam projected from the upper half. The principal crescent-shaped beam projected by the upper half of the reflector will pass through the clear portion 19 of the lens, while the inverted and superimposed crescent-shaped beam from the lower half of the reflector will be intercepted by the prisms provided on the lower half of the lens, whereby the superimposed beam will be spread laterally so as to diverge from the axis of the beam for lighting up the sides of the road and ditches.

Thus, in effect, there are provided two principal beams projected by the reflector, one from the upper portion of the reflector and one from the lower, said beams being superimposed one upon the other, the light beams from the upper portion freely passing

through the clear portion 19 of the lens so as to give a bright driving light at a distance down the road, while the beam from the lower portion of the reflector accomplishes the desired spreading effect when this particular lens is employed in conjunction with the above-mentioned reflector. As above stated, however, the side prisms of the lens will act to gather in some of the extreme lateral rays and bend them towards the axis so as to increase the amount of light projected down the road. In addition to the above, the direct rays from the source of illumination will be refracted by the prisms of the lower portion of the lens for spreading the same over the surface of the road immediately in front of the vehicle.

The invention claimed is:

1. A lens for a headlight comprising a central portion having a series of vertically-extending prisms extending thereacross, said series comprising a central group of prisms for refracting light in opposite directions and effecting a lateral distribution thereof, the upper ends of said prisms terminating substantially in a horizontal plane through the center of the lens, said lens being free from prisms above such horizontal plane for freely emitting light therethrough without substantial refraction, and a plurality of vertically extending prisms on each side of said first-mentioned group of prisms comprising means for refracting light towards the axis of the lens.

2. A headlight including a concave reflector, a source of light and a lens associated therewith, said lens having a series of vertically-extending prisms extending thereacross, said series comprising a central group and a group on each side thereof, the prisms of said central group being materially shorter than the prisms of the side group to leave the upper central portion of said lens non-refractive, said prisms constituting means for refracting light projected from said reflector toward the vertical plane of the center of the beam and for refracting a portion of the direct light from said source away from said plane.

3. A lens for a headlight comprising a flattened conical front and a marginal flange, the surface of said front having a series of vertically extending prisms formed therein, the prisms at each side of the front extending substantially equal distances above and below the axis, said prisms being constructed to throw the light toward said axis, and the intermediate prisms having their upper ends terminating below the ends of the side prisms, said intermediate prisms being symmetrical to spread the light horizontally in both directions.

In witness whereof, I have hereunto affixed my signature.

WALTER D'ARCY RYAN.
